UNITED STATES PATENT OFFICE.

JAMES J. MULCONROY, OF PHILADELPHIA, PENNSYLVANIA.

DESIGN FOR A REMOVABLE CAP FOR TELEPHONE RECEIVING INSTRUMENTS.

SPECIFICATION forming part of Design No. 29,707, dated November 22, 1898.

Application filed May 7, 1898. Serial No. 680,070. Term of patent 7 years.

To all whom it may concern:

Be it known that I, JAMES J. MULCONROY, a citizen of the United States, residing in the city and county of Philadelphia, in the State of Pennsylvania, have invented and produced a new and original Design for a Removable Cap for Telephone Receiving Instruments, of which the following is a specification.

In the accompanying drawings, 10 Figure 1 is a view in perspective of a removable cap for a telephone receiving instrument showing my design.

Figure 2 is a central, sectional, elevation of the same.

15 As shown in the drawings, the leading or material feature of my design consists of a plate or disk A having a central aperture a and an annular concentric corrugation B, the

outer edge of which disk is provided with a depending circumferential flange C, the disk or plate being of an approximately uniform thickness from edge to edge. 20

Having thus described my invention, what I claim, and desire to secure by Letters Patent, is— 25

The design for a removable cap for a telephone receiving instrument as herein shown and described.

In testimony that I claim the foregoing as my invention I have hereunto signed my name 30 this 5th day of May, A. D. 1898.

JAMES J. MULCONROY.

In presence of—

F. NORMAN DIXON,
THOS. K. LANCASTER.
